Samuel M. M. Jr.
F. W. Griswold

INVENTOR.

John Moses

UNITED STATES PATENT OFFICE.

JOHN MOSES, OF TRENTON, NEW JERSEY.

DESIGN FOR A DISH.

SPECIFICATION forming part of Design No. 14,328, dated September 25, 1883.

Application filed July 19, 1883. Term of patent 7 years.

To all whom it may concern:

Be it known that I, JOHN MOSES, a citizen of the United States, residing at Trenton, in the county of Mercer and State of New Jersey, 5 have invented a new and original Design for Vegetable-Dishes, of which the following is a specification.

The accompanying drawings show my invention.

10 In the drawings, in which similar letters of reference indicate similar parts, Figure 1 shows the outline design or shape of my dish, while Fig. 2, which is a top view of the cover of the dish, shows the shape of the sides and 15 ends of such cover and dish.

My dish has flaring sides, slightly convex on the outer side, and surmounted by the core A. This core is surmounted by a bead at the top of the dish. At the bottom of the body A of the 20 dish is another bead, and below this are the feet D. These feet are irregular in outline, and each one is provided with a scroll-bead, D'. The

sides and ends of the dish are of the outline shape shown in Fig. 2. This outline shape is shown very nearly in Design Patent No. 13,005, 25 and I do not claim it, broadly, by itself alone. The handles C are supported upon pedestals having square feet. The handles are slightly bowed on top, and are provided with a square central portion, within which is impressed a 30 rosette. Around this rosette, and passing along the sides of the handles and down the pedestals and on the bases, is a rib in relief.

What I claim as my invention is—

1. A dish of the general outline shape shown 35 and described.
2. A dish of the general outline shape shown and described, provided with handles of the design shown and described.

JOHN MOSES.

Witnesses:

SAMUEL WALKER, Jr.,
F. W. G. NICHTEL.

It is hereby certified that in Letters Patent No. 14,328, granted September 25, 1883, upon the application of John Moses, of Trenton, New Jersey, for a design for a "Dish," an error was committed requiring correction as follows: The word "core" should be read *cove* wherever it occurs in the printed specification; and that the patent should be read with this correction therein to make it conform to the record of the case in the Patent Office.

Signed, countersigned, and sealed this 6th day of November, A. D. 1883.

[SEAL.]

M. L. JOSLYN,
Acting Secretary of the Interior.

Countersigned:

BENJ. BUTTERWORTH,
Commissioner of Patents.
